UNITED STATES PATENT OFFICE.

SILAS VEROY, OF TORONTO, CANADA.

TROLLEY-POLE.

SPECIFICATION forming part of Letters Patent No. 636,189, dated October 31, 1899.

Application filed January 20, 1899. Serial No. 702,784. (No model.)

To all whom it may concern:

Be it known that I, SILAS VEROY, of Toronto, in the Province of Ontario and Dominion of Canada, have invented a new and Improved Trolley-Pole, of which the following is a full, clear, and exact description.

This invention relates to trolley-poles and attachments thereto for double-wire electric-car systems; and the object is to provide a device of this character that may be readily applied to cars employing the present devices at a comparatively small cost, as well as to new cars.

I will describe a trolley-pole and its attachments embodying my invention and then point out the novel features in the appended claims.

Reference is to be had to the accompanying drawings, forming a part of this specification, in which similar characters of reference indicate corresponding parts in all the figures.

Figure 1 is a partial section and a partial side elevation of a trolley-pole and attachments embodying my invention. Fig. 2 is a section on the line 2 2 of Fig. 1. Fig. 3 is a sectional view of the upper portion of the pole, and Fig. 4 is an inner face view of the turn-table portions employed.

Referring to the drawings, 1 designates a tubular trolley-pole, of the usual material, having a cross-head 2 at its lower end, provided with trunnions 3, having bearings in uprights 4, attached to a base-plate 5. The trolleys carried by the pole are held in yielding engagement with the wires by means of springs 6, which surround the cross-head 2 and have one end connected to said cross-head and the other ends connected to the uprights.

Attached to the upper end of the pole 1 is a coupling 7, having divergent tubular members 8, into which the lower ends of the tubes 9 are engaged. These tubes 9 are engaged at the upper end with couplings 10, with which the shanks 11 of the blocks 12 engage. These shanks and the blocks are insulated from the coupling stem, as plainly shown in Fig. 3. Mounted in the blocks 12 are the trolleys 13 14, one designed to engage with the wire 15 and the other to engage with the wire 16, these wires 15 and 16 being the main and return wires of the double-wire system. Obviously

the parts 8, 9, and 10 may be considered as a single arm, the two arms of course divergent, as shown.

Secured to the under side of the base 5 is a ring 17, of insulating material—such, for instance, as indurated fiber. Seated in this ring at diametrically opposite points are segmental contact-plates 18. The ring 17 is designed to turn upon a ring 19, of insulating material, secured to the roof 20 of the car in any suitable manner, and in this ring 19 are seated segmental contact-plates 21, adapted to be engaged by the contact-plates 18. The conductor 22 has electrical connection with the trolley 13 and extends downward through the pole and through an opening in the cross-head 2 to connection with one of the contact-plates 18, and a conductor 23 provides connections between the trolley 14 and the other contact-plate 18.

From the contact-plates 21 wires 24 and 25 extend to a connection with the motor of a car or to wires in the roof having connection with the motor. A king-bolt 26 extends through the base-plate 5 and also through the roof or platform of the car and is suitably insulated from both.

The contact-plates 18 and 21 being quite long, the pole is well adapted for preserving the electrical connections while a car is going around curves and when the pole is laterally deflected to a considerable extent relatively to the car. In other words, from this construction it is evident that independent connections are maintained at all times between the trolleys and the wires 24 25, leading to the motor, no matter on how sharp or how long a curve the car may be running. In ordinary trolley systems in which the rail or track is used for the return-current trouble is caused by the leakage of the current from the rails, which results in the destruction by electrolysis of neighboring water and gas pipes and the steel foundations of large buildings and also causing a great loss to the railway company by the leakage of electricity through the ground. As I employ a separate wire for the incoming current and a separate wire for the outgoing current no difficulty of this kind will be experienced.

Parts of my invention may be changed in form and proportion without departing from

the spirit or sacrificing the advantages of my invention.

Having thus fully described my invention, I claim as new and desire to secure by Letters

5 Patent—

1. A trolley-pole and connections for a double-wire overhead electric-car-line system, comprising a tubular pole, divergent tubes extended from the upper end of said pole, trolley-blocks supported at the upper ends of said tubes, but insulated therefrom, trolleys mounted in the blocks and means comprising wires extended through the pole and tubes, for completing a circuit between the trolleys and the

15 motor of a car, substantially as specified.

2. A trolley-pole and connections for a double-wire overhead electric-car-line system, comprising a tubular pole, a coupling on the upper end of said pole and having divergent tubular members, tubes connected in said members, couplings engaging the upper ends of said tubes, trolley-blocks supported in said last-named couplings but insulated therefrom, and trolleys mounted in the blocks, substantially as specified. 20
